UNITED STATES PATENT OFFICE.

FRANK L. NICHOLS, OF NEW YORK, N. Y., AND WILLIAM M. FOWLER, OF STAMFORD, CONNECTICUT, ASSIGNEES, BY DIRECT AND MESNE ASSIGNMENTS, TO THE NEW IDEAS MACHINE COMPANY, OF WEST VIRGINIA:

BOTTLE-FILLING MACHINE.

SPECIFICATION forming part of Letters Patent No. 662,087, dated November 20, 1900.

Application filed May 23, 1900. Serial No. 17,631. (No model.)

To all whom it may concern:

Be it known that we, FRANK L. NICHOLS, of the city of New York, (Brooklyn,) county of Kings, State of New York, and WILLIAM MILES FOWLER, of Stamford, county of Fairfield, State of Connecticut, citizens of the United States, have invented certain new and useful Improvements in Bottle-Filling Machines, of which the following is a full, clear, and exact description, reference being had to the accompanying drawings, forming part of this specification.

This invention relates to a machine for filling bottles and other vessels in which a series of filler-tips is carried by a reciprocatory head and in which the bottles or vessels to be filled, arranged in successive parallel ranks in a group or bank, have their ranks successively presented to the filler-tips, so that said tips respectively will enter the mouths or filling-apertures of the members of a rank thereof in performing the filling operation during the thrust of the tip-bearing head toward them; and it also relates to a machine of this class in which the reciprocatory tip-bearing head is carried and actuated by bars having longitudinal play in ways provided in standards on the machine-frame; and it further relates to a machine of this class in which each filler-tip of the series thereof carried by a reciprocatory head has individual communication, respectively, with a supply-reservoir and a drainage-chamber carried by said head and common to the series of tips for the inlet of filling fluid or material to and the outlet of air and any overflow from said tips.

This invention consists, primarily, in the combination, with the tip-bearing head in a machine of the class stated, of filler-tips movably seated at their upward ends in a series in said head and adjustable thereon at determinate and uniform distances apart successively, whereby the filler-tips of the series thereof may be adjusted to register with and enter the mouths or filling-apertures of bottles or vessels of any uniform diameter presented to said series of tips in a rank; and the invention further comprises the combination, with the tip-bearing head in a machine of this class and filler-tips movably seated at their

upward ends in a series in said head, together with a supply-reservoir and a drainage-chamber respectively common to the series of tips, of flexible or yielding and extendible connections severally establishing communication between said reservoir and the fluid-inlet of each filler-tip and between the air and overflow outlet of each said tip and said drainage-chamber, whereby the adjustment of the filler-tips relatively to each other in said head may be made and the necessary communications between each said tip and the said reservoir and drainage-chamber be at all times maintained; and the invention still further comprises the novel structural features in a machine of this class hereinafter particularly described and as more at length recited in the claims.

In the drawings, Figure 1 is a front elevation, partly sectional, of the tip-bearing head and the standards in which it has reciprocatory movement. Fig. 2 is a plan of the device detached from the tip-bearing head, which is desirably employed to engage and effect the adjustment of the filler-tips relatively to each other on said head. Fig. 3 is a vertical sectional view, enlarged, on line xx through the tip-bearing head and the supply-reservoir and drainage-chamber and illustrating a flexible or yielding and extendible connection between a filler-tip of the series thereof on said head and said reservoir and chamber; and Fig. 4 is an elevation of the inner face of one of the standards in which the tip-bearing head reciprocates.

It will be understood that in the machine to which this invention relates means, such as a platform or table having movement across the plane of the path of movement of the reciprocatory tip-bearing head, is employed on which the bottles or other vessels to be filled are arranged in successive parallel ranks in a group or bank, and that said ranks thereof are successively moved to position under the reciprocatory head, so that the mouths or filling-apertures of the bottles or vessels will severally register with and during a downward thrust of said head be entered by the filler-tips on said head. Such bottle supporting and moving means is not shown.

herein, as no feature of the invention relates thereto, and the nature and function thereof will be understood.

A is the tip-bearing head, which extends laterally of the machine and is desirably provided with the brackets a at its respective opposite ends that are connected to bars B, which severally are seated in and have play longitudinally of ways b, provided on the inward faces of the standards B', rising on the machine-frame, whereby the head A has reciprocatory movement vertically on said standards. The bars B are desirably given a reciprocatory movement in their said ways by a link b', connecting each said bar with similar crank-arms b² on a rock-shaft b³, as shown in Fig. 4. The said tip-bearing head in machines of this class is usually given an adjustability longitudinally of the bars B, as by slots or notches b⁴ in the bars, formed correspondingly in series longitudinally thereof, together with spring-actuated bolts a⁶, working in recesses in the brackets a and severally engaging corresponding slots or notches in the respective bars and controlled by crank-levers a⁷, playing in said recesses with one arm engaging its bolt a⁶ and the other arm a⁸ projecting beyond the bracket, so that the levers and bolts can be readily manipulated. This movability of the head A on its supporting bars B permits the head to be adjusted, as desired, relatively to the height of the bottles or vessels to be filled, which are carried by a platform, as described, across the plane of the path of movement of said head.

In carrying out a feature of the invention the filler-tips C are adjustable relatively to each other on the head A at determinate and uniform distances apart successively; and such adjustability of the tips is desirably simultaneous for each one of the series thereof, and for this purpose it is desirable that the tips C be mounted on the head A by means of sockets C', in which the tips are severally screw-seated, Fig. 3, and that said sockets be severally provided with flanged heads which reach into a longitudinal recess a' in the head A and with said flanges seating and playing in longitudinal ways a⁹ in the wall of said recess, and for economy in construction and convenience in the assembling of the parts the flanges on the socket-heads are desirably constituted of plates c; preferably rectangular, which are fastened by bolts c' to the upper ends of the said socket-head c², as indicated in Figs. 2 and 3, and, furthermore, that the tips C of the series thereof be severally engaged and connected by a lazy-tongs device, as indicated at D. In arranging this lazy-tongs device the tongs should be composed of links d of uniform lengths, as illustrated in Fig. 2, and with transverse apertures d' in the pivotal joints of the arms constituting the respective links, as shown, and it is desirable that the engagement of the tongs D with the filler-tips be made by seating the upper cy-

lindrical ends c² of the tip-sockets C' in and through the apertures d' in the tongs-links and that a shoulder c³ be provided on each socket-head to meet the under face of the tongs-link, together with a sleeve c⁴ on the socket-head c² between the upper face of the tongs-link and the under side of the flange-plate c. Moreover, in employing the tongs D it is desirable to provide a stud d², extending from one of the pivotal connections of the tongs-links and preferably from the central connection of the series of said links, which stud reaches to and engages and has play in a way a⁴ on the head A and which way a⁴ may be formed in the under face of a bracket a⁵, bolted upon and extending laterally from the front side of said head A. By means of said stud d² the tongs D will be maintained in proper position relatively to the head A during the movements of the tongs and tips in effecting the adjustment of the latter in the head relatively to each other.

It is evident that by means of the described devices the tips C of the series thereof may readily and conveniently be simultaneously adjusted at determinate and uniform distances apart successively, so that the filler-tips carried by the head A may at the pleasure of the operator of the machine be quickly adjusted to register with and enter the mouths or filling-apertures of bottles or other vessels of any uniform lateral diameter arranged and presented to the series of said tips in successive parallel ranks.

In carrying out a further feature of the invention a flexible or yielding and extensible connection, as at E, establishes communication between a supply-reservoir F and the fluid-inlet to each filler-tip of the series thereof, and a similar connection, as at E', establishes communication between the air-vent and overflow of each said filler-tip and a drainage-chamber F', as illustrated in Fig. 3.

It is desirable that the tip-sockets C' be severally formed with the space or chamber c⁵ therein above the upper end of the filler-tip seated therein and with which the inlet c⁶ of the tip-communicates and with the internal circumferential groove c⁷ in the socket-wall to register with a groove c⁸ on the tip-head, into which the air-vent and overflow-passage of said tip opens, as at c⁹, and the sockets are also desirably provided with laterally-extended nipples c¹⁰ and c¹¹, respectively leading from said chambers c⁵ and grooves c⁷ therein. It is also desirable that the reservoir F and the overflow or drainage chamber F', which are common to the series of filler-tips, as indicated in Fig. 1, be mounted on the head A in the manner shown—that is to say, with the drainage-chamber F' supported directly by a bracket or brackets a⁹ on and extended rearwardly of said head, as shown in Fig. 3, and with the reservoir F seated on top of said chamber F', as indicated. The reservoir F is preferably cylindrical, as shown, and the upper side of the chamber F' may be corre-

spondingly concave throughout its length to give a saddle-seat for the reservoir, as illustrated in Fig. 3. A fluid-inlet for the reservoir F may be provided at f, and the chamber 5 F' is conveniently given an outlet through a drainage-tube f', which may discharge into a receptacle placed at the side of the machine.

In the wall of the reservoir F an outlet-aperture f² is provided for individual communication therefrom to each of the tips of the series thereof, and the said reservoir and the chamber F' being arranged as described a plug G, Fig. 3, is provided to pass through an outwardly-flanged aperture f³ in the bottom wall in the chamber F' and into an inwardly-flanged aperture f² in the opposite wall thereof coincident to an aperture in the bottom of the reservoir, and said plug is preferably conical or tapering and seats to correspondingly-flared internal faces on the flanges of said apertures f² f³ and is held to its seat by a collar g, screwed exteriorly of the flange on aperture f³ and having an internally-projecting flange g' to engage an external shoulder g² on the plug. The plug has the passage g³, leading directly through it and communicating with the reservoir F, and the passage g⁴, leading through it to one side thereof and opening laterally thereof to communicate 25 with the chamber F'. The plug is desirably provided at its outward end with preferably radially or horizontally turned nipples g⁵ g⁶, respectively leading from the passages g³ g⁴. It is to be understood that the plugs G are employed in a series corresponding in number 30 to that of the filler-tips, and the nipples g⁵ and g⁶ on each plug of the series thereof may severally be given a flexible or yielding and extendible connection with the respective nipples c¹⁰ c¹¹ on corresponding tip-sockets C' of the series thereof by the respective tubes E and E', which are desirably formed of soft 35 rubber and given a length to reach severally between the respective nipples c¹⁰ g⁵ and c¹¹ g⁶ when the sockets carrying the tips are adjusted on the head A at their widest limit of 40 distance apart, the described formation of the tubes E and E' being such that they will accommodate themselves to a shortening of 45 the distances between the respective nipples to which they are joined when the tip-sockets and tips are adjusted more closely together 50 on the head A.

It is evident that by means of the described 55 devices arranged as set forth the adjustment of the filler-tips C relatively to each other on the head, as hereinbefore described and for the purpose hereinbefore stated, may be made and the necessary communications between each said tip and the said reservoir and drainage-chamber be at all times maintained.

It should be understood that the invention 60 is not limited to the particular devices herein shown and described whereby the adjustability of the filler-tips relatively to each other on the reciprocating head and the

yielding and extendible connections set forth between the filler-tips and the supply-reservoir and drainage-chamber are attained, but 70 that any other known and equivalent devices may be employed for any or all of said purposes without substantial variation from the stated features of the invention.

It is evident that a filling-machine containing the described features of this invention will be capable of being quickly and easily adjusted to effect the filling of bottles or vessels of various and different dimensions, the bottles or vessels of any one uniform dimension being arranged in ranks, each of which is composed of said bottles or vessels corresponding in number to the number of filler-tips of the series thereof in the machine, and said ranks being presented to said 85 series of tips in the usual and well-known manner in machines of this class.

What we claim as our invention, and desire to secure by Letters Patent, is—

1. In a bottle-filling machine the combination with the tip-supporting head, of filler-tips severally movably and connectedly seated at their upward ends, in a series, in ways in said head, and simultaneously fixedly adjustable thereon at determinate uniform distances 90 apart successively in said ways.

2. In a bottle-filling machine, the combination with the tip-supporting head, of filler-tips severally movably seated at their upward ends, in a series, in ways in said head, 100 and a lazy-tongs device common to and operatively connecting the several filler-tips of the series thereof.

3. In a bottle-filling machine the combination with the tip-supporting head, of filler-tips carried in a series by said head and severally movable thereon relatively to each other, together with a lazy-tongs device composed of links of uniform lengths and having transverse apertures in the pivotal joints of 105 the arms constituting the respective links thereof, and pivotal heads or bearings respectively provided on each filler-tip and severally seated in said transverse apertures in the tongs-links.

4. In a bottle-filling machine the combination with the tip-supporting head, of filler-tips carried in a series by said head and severally movable thereon relatively to each other, together with a lazy-tongs device composed 110 of links of uniform lengths, pivotal heads or bearings respectively provided on each filler-tip and severally seated in transverse apertures in the pivotal joints of the pairs of arms constituting the respective tongs-links, and 115 a stud in a pivotal connection between links of said tongs and reaching to, engaging and having play in a guideway on the tip-supporting head.

5. In a bottle-filling machine the combination with the tip-supporting head, of filler-tips carried in a series by said head and severally movable thereon, a lazy-tongs device composed of links of uniform lengths, pivotal

heads or bearings respectively provided on each filler-tip and severally seated in transverse apertures in the pivotal joints of the pairs of arms constituting a similar number 5 of links in the respective portions of the tongs beyond the joints between the links at the middle of said tongs, and a stud projecting from a joint between the links at said middle of said tongs and reaching to, engaging and 10 having play in a guideway on the tip-supporting head.

6. In a bottle-filling machine the combination with the tip-supporting head having a longitudinal recess in its downward face with 15 longitudinal ways in the wall of said recess, of filler-tips severally provided at their upward ends with lateral flanges to engage and play in said ways in said recess in the tip-supporting head.

20 7. In a bottle-filling machine the combination with the tip-supporting head having a longitudinal recess in its downward face with longitudinal ways in the wall of said recess, of a series of sockets, each having a body into 25 which the upper end of a filler-tip seats and a head which reaches into said recess in the tip-supporting head and carries a lateral flange which engages and plays in the ways in said recess-wall.

30 8. In a bottle-filling machine, the combination with the tip-supporting head having a longitudinal recess in its downward face with longitudinal ways in the wall of said recess, of a series of sockets, each having a body into 35 which the upper end of a filler-tip seats and a cylindrical head which reaches into said recess, a laterally-projecting flange-plate secured to the top of said head with its edges seated and playing in said ways in the recess-

40 wall, a lazy-tongs device having transverse apertures in the pivotal joints of the pairs of arms composing the tongs-links and through which apertures the cylindrical heads of the sockets severally pass, a shoulder on each 45 socket-body to which the under faces of the respective tongs-links severally engage, and sleeves on the socket-heads between the upward faces of the tongs-links and the under faces of the flange-plates on said socket-heads.

50 9. In a bottle-filling machine the combination with a tip-supporting head, of filler-tips movably seated at their upward ends, in a series, in ways in said head, and severally provided at their said upward ends with an inlet 55 to the filler-tube of the tip and an outlet from the air and overflow vent thereof, together with a supply-reservoir and a separate drainage-chamber carried by said head, and flexible, extendible connections respectively es- 60 tablishing communication between the said reservoir and the filler-tube inlet of each tip and between the air and overflow outlet of each said tip and said drainage-chamber.

10. In a bottle-filling machine the combination with a tip-supporting head and a supply-reservoir and separate drainage-chamber carried by said head, of a series of sockets

severally provided with heads which are movably seated in ways in the tip-supporting head and bodies which severally receive the upward ends of and sustain filler-tips of a series thereof, and also severally provided with passages respectively communicating with the filler-tube and the air and overflow vent of each filler-tip, together with plugs, in a series, 70 severally provided with passages respectively leading from said reservoir and into said drainage-chamber, and yielding or flexible and extendible connections severally establishing communication respectively between the reservoir outlet-passages in said plugs and the filler-tube inlet-passages in said sockets, and between the air and overflow passages in 75 said sockets and the drainage-chamber inlet-passages in said plugs.

80 11. In a bottle-filling machine the combination with a tip-supporting head, filler-tips carried in a series by said head and movably seated therein, and a fluid-supply reservoir and a drainage-chamber, in juxtaposition and common to the series of tips and having coincident apertures in their conjunctive walls and apertures registering therewith in the opposite wall of said drainage-chamber, of plugs severally seated in said apertures in the 90 reservoir and chamber walls and provided with passages respectively communicating with said reservoir and chamber, together with nipples respectively leading from said 95 passages, and flexible or yielding and extendible connections respectively establishing communication between said reservoir-passage nipples and the fluid-inlets of the several filler-tips and between the air and overflow outlets of said several tips and the drainage-chamber-passage nipples on said plugs.

100 12. In a bottle-filling machine, the combination with the reciprocatory head which carries a series of filler-tips, of a drainage-chamber, common to said tips and seated upon said head, and having an inwardly-concave top wall provided with inwardly flanged and flared apertures therein and with outwardly flanged and flared apertures in its bottom wall, severally registering with the apertures 115 in the top wall, a cylindrical supply-reservoir seated on the concave top wall of said chamber and having apertures in its wall coincident with the apertures in said top wall of the drainage-chamber, and tapering or conical 120 plugs, severally seated in said apertures in the bottom wall of said chamber and the coincident apertures in the top wall of said chamber and the wall of said reservoir, and provided with passages respectively communicating with said coincident apertures in 125 said walls of said reservoir and drainage-chamber and with said drainage-chamber, together with a flanged collar seated upon the flange of each aperture in the bottom wall of 130 said chamber and engaging a circumferential shoulder on each said plug.

13. In a bottle-filling machine in which the fluid-supply reservoir and the drainage-cham-

ber are located in juxtaposition with the former above the latter and with coincident apertures in their adjacent walls and a flaring flange projecting inwardly of said chamber 5 around the said aperture in said wall thereof, together with an outwardly flared and flanged aperture in the opposite wall of said chamber registering with said coincident apertures, a plug having a tapering body, to seat in said 10 flanged apertures in said chamber-walls, and a larger passage longitudinally through it, to communicate with the aperture in said chamber - wall leading to said reservoir, and a smaller passage leading from the outward end 15 of the plug to an opening in its side, to communicate with said chamber, and provided with radially or laterally turned nipples severally leading, at the outward end of the plug, from said respective passages therein.

20 14. In a bottle-filling machine in which filler-tips are seated, in a series, in a support-

ing-head, a socket to individually sustain each said filler-tip in said head, composed of a top to seat in said head and a body to receive and seat the threaded upper end of the tip and 25 having a chamber above said upper end of the seated tip with which the fluid-inlet of the tip communicates, and an internal circumferential groove to register with a corresponding external circumferential groove on the tip 30 into which the air and overflow vent of the tip opens, together with lateral apertures in the socket-wall respectively leading from said chamber and groove in said body thereof.

Signed at New York city, State of New York, 35 this 11th day of May, A. D. 1900.
